UNITED STATES PATENT OFFICE.

LEONARD THOMAS RIDGLEY, OF ASHLAND, OHIO.

BUSTLE.

SPECIFICATION forming part of Letters Patent No. 400,115, dated March 26, 1889.

Application filed August 25, 1888. Serial No. 283,732. (Model.)

To all whom it may concern:

Be it known that I, LEONARD THOMAS RIDGLEY, a citizen of the United States, residing at Ashland, in the county of Ashland 5 and State of Ohio, have invented certain new and useful Improvements in Bustles; and I do hereby declare the following to be a full, clear, and exact description of the invention, such as will enable others skilled in the art to 10 which it appertains to make and use the same.

My invention relates to an improvement in bustles; and it consists in the construction and arrangement of parts hereinafter described, and definitely pointed out in the 15 claims.

The object of my invention is to provide a cheap and durable bustle, one which will be normally expanded in a manner to form the desired curvature and protuberance and 20 quickly and easily collapsed when occasion demands. I attain this object by the construction illustrated in the accompanying drawings, wherein like letters of reference indicate corresponding parts in the several 25 views, and in which—

Figure 1 is a side elevation view of my improved bustle expanded, and Fig. 2 is a bottom view showing the expanding-springs.

In the drawings, A represents a spiral 30 spring formed by a single strand of wire, the coils of which gradually decrease in diameter from the first or forward coil, and finally terminate in a small spiral or curved end, as a, bent and retained in the last coil of the 35 spring, thus forming a closure for the outer end of the spring. This spring is in size sufficient to form a complete bustle when properly expanded. To add rigidity to the forward coil, and for purposes hereinafter stated, I se- 40 cure a cross-piece or brace, B, to the opposite sides of the coil near its lower portion. This brace or cross-piece has two inwardly-extending eyes, b, formed by looping the wire forming the brace at points midway the center and 45 the respective ends thereof.

To give the desired shape to the bustle and to prevent the lateral displacement of the coils, they are gathered at their lower sides and loosely bound or held together by the 50 coils of springs C, which encircle the same.

These springs C are formed of separate pieces of wire located side by side, their inner ends, c, being carried up tangentially and bent outwardly to the loops b of the bar B, at which point they are secured. The opposite or outer 55 arms or ends, c', of the springs C are, in a manner similar to the inner ends, but at right angles thereto, carried out from the coils and extended up to the top of the end or outer coil of the spring A, at each side thereof, at 60 which point they are secured.

To prevent the springs C from separating, they are bound together by a wire, as c''. A connecting-band or retaining-cord, D, is ex- 65 tended from the top of the forward coil to the rear coil, it being united with each of the intermediate coils to retain them an equidis- tance apart when expanded.

To insure a perfect expansion of the bustle, I provide an auxiliary spring, E, located 70 within the coils. It is formed of a single wire wound spirally, with its ends abutting and fastened to the cross-bar B, the end a, and the top of the end coil of the spring A, between the arms c' of the springs C. This spring col- 75 lapses when the spring A is collapsed. A fur- ther advantage gained by the use of spring E is that on the occasion of the breaking or bend- ing of the springs C the bustle will still be useful, the spring E alone being sufficient to 80 expand the coils.

It will be understood that the entire con- struction above described may be incased in a suitable covering, and also that the waist- 85 band is to be attached to the top of the first or inner coil of spring A. When the bustle is collapsed, the ends of the arms on springs C are brought toward each other, the resiliency of the coils being overcome and immediately forcing the coils of spring A apart when the 90 pressure thereon is relieved. By this con- struction I am enabled to secure a more per- fect working bustle than has been the case heretofore in this class, the extended arms 95 of the springs C acting as levers to force both the forward and rear coils immediately out.

I am aware that many minor changes in the construction and arrangement of the parts of my improvement can be made and substituted for those shown and described without in the 100

least departing from the nature and principle of my invention.

Having thus described my invention, what I claim as new, and desire to secure by Letters

5 Patent, is—

1. In a bustle, the combination, with a single coiled-wire spring having its lower side gathered, of a spring coiled on and securing said gathered portion, the ends of said spring 10 being carried out in opposite directions and secured, respectively, to the front and rear coil of said spring, and a coiled spring within said spiral spring, substantially as described.
2. In a bustle, the combination, with a sin-

gle coiled spring having a cross-bar, as B, on its forward coil and its lower portion gathered, of springs, as C, coiled on said gathered portion, the ends *c* and *c'* of said latter springs being extended out in opposite directions and secured, respectively, to said cross-bar and the outer coil of the spiral spring, substantially as described.

In testimony whereof I affix my signature in presence of two witnesses.

LEONARD THOMAS RIDGLEY.
